APPARATUS FOR PACKAGING VENETIAN
BLIND INSTALLATION BRACKETSHans K. Lorentzen, Montclair, N. J., assignor to
Lorentzen Hardware Mfg. Corp., New York,
N. Y., a corporation of New York

Application September 23, 1949, Serial No. 117,419

6 Claims. (Cl. 226—2)

1

This invention relates to a device for facilitating the packaging of Venetian blind installation brackets.

Venetian blind installation brackets are usually formed of sheet metal stampings, and have a more or less square or rectangular outline. These brackets are customarily given a painted or enamelled finish. It is often desirable to package the brackets in pairs, since a pair of brackets is required for the installation of one blind. A pair of brackets consists of a right-hand and left-hand bracket which are nested together and placed, together with wood screws for mounting the brackets, in a small bag, usually a paper bag.

In order not to mar the front and outer side surfaces of the brackets, they are so nested that, when inserted in the bag, these surfaces of one bracket are not in contact with the outer bracket but are against the inside surface of the bag. However, the mounting screws have a tendency to slip between the outside surface of the bracket and the bag and mar the outside surface.

To overcome the marring of the surfaces of the installation brackets by the screws, the required number of screws are inserted into the bag between the brackets of the nested pair, the bag closely fitting about the brackets so that there is insufficient room for the screws to slip between the brackets and the bag. To further alleviate the possibility of marring and to facilitate packaging, the required number of screws for one pair of brackets may be united by a covering strip of paper.

The present invention is directed to a device for facilitating such packaging of installation brackets and mounting screws. In the form shown, this device comprises a chute which extends downwardly and forwardly towards the operator and is proportioned to telescopically receive a bag and hold the bag in extended open position. A pair of brackets is nested on an assembly area adjoining the chute and is then inserted as a unit into the bag by sliding the brackets laterally and then permitting them to slide down the chute into the bag.

Above the chute, and in alignment therewith, a receptacle is preferably provided to hold a supply of screws, one paper of screws being passed down the chute and into each bag either before or after inserting the brackets into the bag. After the brackets and screws are inserted within the bag, the bag is stripped from the chute and the open end folded over or otherwise closed.

An object of the present invention is to provide a device for expeditiously bagging Venetian blind installation brackets.

2

Another object is to provide such a device which facilitates the nesting of the brackets prior to insertion into the bag.

Additional objects are to provide such a device in which insertion of mounting screws into the bag is also facilitated, and to provide such a device that is durable and may be rapidly and inexpensively manufactured from sheet metal stampings.

10 Further objects, and objects relating to details and economies of construction, manufacture and use will more definitely appear from the detailed description to follow.

My invention is clearly defined in the appended claims. In the claims, as well as in the description, parts may at times be identified by specific names for clarity and convenience, but such nomenclature is to be understood as having the broadest meaning consistent with the context and 15 concept of my invention as distinguished from the pertinent prior art. The best form in which I have contemplated applying my invention is illustrated in the accompanying drawings forming part of this specification, in which:

20 Fig. 1 is an isometric view of the packaging apparatus, per se.

Fig. 2 is a view similar to Fig. 1, a supply of bags, a supply of screws, and one bracket being shown in conjunction with the apparatus.

25 Fig. 3 is a fragmentary isometric view showing the packaging apparatus, and a nested pair of brackets being inserted into a bag.

Fig. 4 is an isometric view of the bag after the brackets have been inserted.

30 Reference will now be had to the drawings, in which the same reference character will denote the same part throughout the several views. A flat-bottomed, open-top receptacle 10 is provided to hold a supply of wood screws. Four screws are required for mounting a pair of brackets; and preferably four screws 9 are mounted in a paper strip or carrier 11 in such manner that the paper covers the point and thread of each screw. The receptacle 10, is preferably constructed of 35 sheet metal and is supported by upstanding side members 12, one being shown. Each member 12 has a horizontal flange 14 provided with holes for the passage of screws 15, 15, which secure the receptacle 10 to a bench or table 13 at a convenient height.

40 The forward end 16 of the receptacle 10 is provided with a passageway 17 through which the strip 11 of screws may be manually withdrawn as required.

45 An inverted L-member designated as a whole by 19, adjoins the forward end 16 of the receptacle

10 and extends downwardly and forwardly therefrom. Inclined portions of the side members 12 serve to support the L-member 19.

The vertical leg 20 of the L-member is generally aligned with the passageway 17 of the receptacle 10. Upstanding flanges 21 and 22 extend along the sides of the vertical leg 20. The distance between the flanges 21 and 22 is sufficient to just provide convenient clearance for the passage of a nested pair 24 of installation brackets 10 to be bagged, and the flanges 21 and 22 are of a height at least equal to the height of the nested pair 24 of installation brackets, see Fig. 3.

The flanges 21 and 22 together with vertical leg 20 of the L-member form a chute of suitable cross-sectional area to telescopically receive a bag 25, which will closely receive the nested pair 24 of installation brackets, see Figs. 2 and 3. The terminus 26 of the vertical leg 20 of the L-member is convergent to facilitate the telescoping of the bag 25 onto the chute. To further aid the telescoping of the bag onto the chute the ends of the flanges 21 and 22 are tapered as shown in Fig. 1.

The horizontal leg 27 of the L-member 19 provides an assembly area for nesting a pair of installation brackets preliminary to shifting the pair 24 down the chute. An upstanding flange 29 is provided at the bottom of the horizontal leg 27 to hold the brackets 28 (one shown on the assembly area) while they are being nested, see Fig. 2. The flange 29 also acts as a guide for the brackets, while they are being shifted to the chute.

A vertical member 30 adjacent the rear of the receptacle 10 is provided with a shelf 31 to hold a supply of bags 25. Horizontal flanges 34 (one shown) having holes for the passage of screws 15 are located on the bottom of the vertical member 30, whereby the member 30 may be secured as shown to the bench or table. To hold a stack of bags in such manner that the stack will tend to hug the back of member 30, the shelf 31 is preferably inclined rearwardly-downwardly as shown.

The entire apparatus can be economically manufactured from sheet metal stamping, preferably from sheet-steel, which make a durable but inexpensive device that will facilitate the packaging of nested pairs of installation brackets.

To package the installation brackets, the device is mounted near the forward edge of a table or bench 13 at a convenient height. The chute will extend over the front edge of the table, see Figs. 1, 2 and 3. A supply of bags 25 is placed on the shelf 31 and a supply of papers or strips 11 of screws is placed in the receptacle 10. Each strip of screws contains the required number to mount one pair of installation brackets. A supply of left-hand and right-hand installation brackets (not shown) is located adjacent the operator.

A bag 25 is removed from the shelf at the rear, opened and telescoped onto the chute. An installation bracket of one hand is placed in the assembly area of the horizontal leg 27 of the L-member against the flange 29, the bracket being in the oriented position shown in Fig. 2. A bracket of the opposite hand is then placed in up-side-down position over the bracket 28 to make a nested pair 24 of installation brackets. This pair 24 is then shifted to the left to the chute into the bag 25 and, at that time, it is desirable that the operator hold the bag 25 with

5 his left hand to prevent it from being displaced from the chute. A strip 11 of screws is slid down the chute either before or after the nested pair of brackets is slid into the bag. With the screws and brackets in the bag the bag is removed from the chute and flap 32 folded over, see Fig. 4.

The form of bracket 28 which is shown is that disclosed in Nelson U. S. Patent 2,473,293 issued June 14, 1949. The invention is particularly suited for bagging this bracket and other brackets of similar configuration.

I claim:

1. Apparatus to facilitate the bagging of nested pairs of Venetian blind installation brackets together with their mounting screws, said apparatus comprising: an opened-topped flat-bottomed receptacle for holding a supply of mounting screws; a passageway at the forward end of the receptacle through which mounting screws may be manually withdrawn as required; a downwardly and forwardly inclined inverted L-member adjoining the forward end of the receptacle, the vertical leg of the L-member being generally aligned with said opening in the receptacle and having upstanding flanges on the sides thereof, the distance between said flanges being sufficient to provide clearance for the passage of a nested pair of installation brackets to be bagged and said flanges having a height at least equal to the height of a nested pair of installation brackets, said flanges and the vertical leg forming a chute of suitable cross-sectional area to telescopically receive a bag which will closely receive a nested pair of installation brackets, the horizontal leg of the L-member providing an assembly area for nesting a pair of brackets preliminary to shifting the pair down the chute into the bag; and an upstanding flange at the bottom of said assembly area for holding the brackets while they are being nested and thereafter guiding them to the chute.

2. Apparatus to facilitate the bagging of nested pairs of Venetian blind installation brackets together with their mounting screws, said apparatus comprising: an opened-topped receptacle for holding a supply of mounting screws; a passageway at the forward end of the receptacle through which mounting screws may be manually withdrawn as required; and a downwardly and forwardly inclined inverted L-member adjoining the forward end of the receptacle, the vertical leg of the L-member being generally aligned with said opening in the receptacle and having upstanding flanges on the sides thereof, the distance between said flanges being sufficient to provide clearance for the passage of a nested pair of installation brackets to be bagged and said flanges having a height at least equal to the height of a nested pair of installation brackets, said flanges and the vertical leg forming a chute of suitable cross-sectional area to telescopically receive a bag which will closely receive a nested pair of installation brackets, the horizontal leg of the L-member providing an assembly area for nesting a pair of brackets preliminary to shifting the pair down the chute into the bag.

3. Apparatus to facilitate the bagging of nested pairs of Venetian blind installation brackets together with their mounting screws, said apparatus comprising: a receptacle for holding a supply of mounting screws; a passageway at the forward end of the receptacle through which mounting screws may be manually withdrawn as required; a vertical member adjacent the rear of the receptacle having a shelf member for holding a supply

of bags; a downwardly and forwardly inclined inverted L-member adjoining the forward end of the receptacle, the vertical leg of the L-member being generally aligned with said opening in the receptacle and having upstanding flanges on the sides thereof, the distance between said flanges being sufficient to provide clearance for the passage of a nested pair of installation brackets to be bagged and said flanges having a height at least equal to the height of the nested pair of installation brackets, said flanges and the vertical leg forming a chute of suitable cross-sectional area to telescopically receive a bag which will closely receive a nested pair of installation brackets, the terminus of the vertical leg of the L-member being convergent to facilitate the telescoping of the bag onto the chute, the horizontal leg of the L-member providing an assembly area for nesting a pair of brackets preliminary to shifting the pair down the chute into the bag; and an upstanding flange at the bottom of the assembly area for holding the brackets while they are being nested and thereafter guiding them to the chute.

4. Apparatus to facilitate the bagging of nested pairs of Venetian blind installation brackets together with their mounting screws, said apparatus comprising: a receptacle for holding a supply of mounting screws; a passageway at the forward end of the receptacle through which mounting screws may be manually withdrawn as required; an inclined inverted L-member adjoining the forward end of the receptacle, the vertical leg of the L-member having upstanding flanges on the sides thereof, the distance between said flanges being sufficient to provide clearance for the passage of a nested pair of installation brackets to be bagged and said flanges having a height at least equal to the height of the nested pair of installation brackets, said flanges and the vertical leg forming a chute of suitable cross-sectional area to telescopically receive a bag which will closely receive a nested pair of installation brackets, the terminus of the vertical leg of the L-member being convergent to facilitate the telescoping of the bag onto the chute, the horizontal leg of the L-member providing an assembly area for nesting a pair of brackets preliminary to shifting the pair down the chute into the bag; and an upstanding flange at the bottom of the assembly area for holding the brackets while they are being nested and thereafter guiding them to the chute.

5. Apparatus to facilitate the bagging of nested pairs of Venetian blind installation brackets together with their mounting screws, said apparatus comprising: a receptacle for holding a supply of mounting screws; a passageway at the forward end of the receptacle through

which mounting screws may be manually withdrawn as required; and a downwardly and forwardly inclined inverted L-member adjoining the forward end of the receptacle, the vertical leg of the L-member being generally aligned with said opening in the receptacle and having upstanding flanges on the sides thereof, the distance between said flanges being sufficient to provide clearance for the passage of a nested pair of installation brackets to be bagged and said flanges having a height at least equal to the height of the nested pair of installation brackets, said flanges and the vertical leg forming a chute of suitable cross-sectional area to telescopically receive a bag which will closely receive a nested pair of installation brackets, the horizontal leg of the L-member providing an assembly area for nesting a pair of brackets preliminary to shifting the pair down the chute into the bag.

6. Apparatus to facilitate the bagging of nested pairs of Venetian blind installation brackets together with their mounting screws, said apparatus comprising: a receptacle for holding a supply of mounting screws; a passageway at the forward end of the receptacle through which mounting screws may be manually withdrawn as required; and a downwardly and forwardly inclined inverted L-member adjoining the forward end of the receptacle, the vertical leg of the L-member being generally aligned with said opening in the receptacle and having upstanding flanges on the sides thereof, the distance between said flanges being sufficient to provide clearance for the passage of a nested pair of installation brackets to be bagged and said flanges having a height at least equal to the height of the nested pair of installation brackets, said flanges and the vertical leg forming a chute of suitable cross-sectional area to telescopically receive a bag which will closely receive a nested pair of installation brackets, the terminus of the vertical leg of the L-member being convergent to facilitate the telescoping of the bag onto the chute, the horizontal leg of the L-member providing an assembly area for nesting a pair of brackets preliminary to shifting the pair down the chute into the bag.
